FINISHING NAIL

Charles E. Crooks, Chicago, Ill., assignor to Spot-nails, Inc., Chicago, Ill., a corporation of Illinois

Application July 5, 1941, Serial No. 401,083

2 Claims. (Cl. 20—74)

This invention relates to improvements in nails and more particularly concerns finishing nails such as are adapted for securing moldings or finishing strips, or the like, in place.

Conventional finishing nails are formed with small round heads of only slightly larger diameter than the shanks of the nails, so that the heads may be readily countersunk and without the formation of unduly large countersink holes in the surface of the nailed object. Because of this relatively small diameter of the finishing nails' heads, these nails are impractical for securing insulating or wallboard in place, and their hold upon the usually soft, thin wood of molding or finishing strips is insecure. This is particularly manifest with respect to molding strips which are subject to weathering, as in window screens, doors, and the like, where rusting of the finishing nails and decay or disintegration of the wood immediately surrounding the nails and nail heads all too frequently causes failure of the hold of the nails upon the strips.

Another disadvantage of the conventional round headed finishing nails is that they must be applied either by hand or by relatively complicated, cumbersome and generally unsatisfactory stationary nailing machines with resultant high labor costs. In any event countersinking involves a separate manual operation.

In order to gain the advantage of a simple machine method of driving the fasteners, some attempts have been made, with very indifferent results, however, to use staples for securing molding strips and the like in place. Where the staples are heavy enough and large enough to be effective, the relatively large exposed webs or crowns of the staples or the long slot-like countersink holes made thereby, are quite objectionable. If the clearance between the legs of the staples is reduced sufficiently to limit the crowns to an acceptable length, the narrow sections of wood straddled by the legs of the driven staples, and compressed by countersinking of the staples, tend to shear loose from and release the molding. In an attempt to overcome these objections to the use of staples, the staples have been made from wire so thin as to avoid the defects both as to appearance and shearing out. This compromise in weight has failed to remedy the problem because the thin wire quickly rusts through from weathering.

In consequence, there has been a long-felt need for a finishing nail that has reliable holding qualities and durability combined with the adapt-

ability for simple and convenient high speed, accurate machine nailing.

One object of my invention is to provide a practical, reliable finishing nail which can be driven and countersunk by means of a simple stapler-type of driving machine and which has an improved head construction that is not only small enough to present a neat and acceptable appearance at the surface of the nailed object, especially when countersunk, but also enters into such thorough, non-shearing engagement with the nailed object as to prevent pulling therethrough even after extensive weathering.

Another object of my invention is to provide a finishing nail having an improved head that will enter into a novel interlocking relationship with the secured member. By this the finishing nail is adapted for uses to which prior finishing nails were unsuited, such as in securing in place fibrous insulating panels or wallboard and the like.

Still another object of the invention is to provide a finishing nail that may be supplied in adhered or "stick" form for use in a driving machine.

A further object of the invention is to provide an improved finishing nail of the foregoing general character which may be produced from readily available, low cost material by simple, high speed quantity production methods of manufacture.

Other objects and advantages of the invention will be apparent from the following description and the accompanying drawing, in which similar characters of reference indicate similar parts throughout the several views.

Referring to the drawing, of which there is one sheet,

Fig. 1 is an actual size fragmentary perspective view of a section of window screen showing the molding strip secured in place on the frame by means of my improved finishing nail;

Fig. 2 is a more or less schematic vertical sectional view through the driver end of a driving machine with which my improved finishing nail is adapted to be applied in use;

Fig. 3 is a transverse sectional view on an enlarged scale taken substantially along line 3—3 of Fig. 1;

Fig. 4 is a longitudinal sectional view on an enlarged scale taken substantially along line 4—4 of Fig. 1;

Fig. 5 is a perspective view of a series of the finishing nails adhered together in "stick" form for use in the driving machine;

Fig. 6 is a perspective view of one of my finishing nails on an enlarged scale;

Fig. 7 is a perspective view of a modified form of the finishing nail;

Fig. 8 is a perspective view of another modified form of the finishing nail; and

Fig. 9 is a perspective view of a further modified form of the finishing nail.

By way of illustration of an important use for which my finishing nail, generally identified by the numeral 15, is especially well adapted, I have shown the same in fastening association with a wooden window or door screen structure. Such a structure includes a frame 16 which is provided with a rabbet groove 17 for receiving the margin of a screen wire panel 18. The screen wire may be stretched by roller pressing a portion of its margin into a channel shaped groove 19 at the longitudinal center of the engaged face of the groove 17. A thin finishing or molding strip 20 is secured within the groove 17 over the margin of the screen by means of the nails 15 spotted at suitable intervals throughout the length of the strip.

According to my invention the finished nail 15 is of a novel construction adapting it to be driven into the members to be secured together by means of a machine operating on the principles of a staple driving machine. Such a machine may be manually or power driven and may be of small, compact portable construction so that it can be conveniently carried to each point where it is desired to drive a nail.

As shown in Fig. 2, such a machine may comprise a frame 21 having therein a magazine 22 to receive a substantial quantity of the nails in series along a supporting and guiding bar 23. Means (not shown) pushes the series of nails along the supporting bar 23 successively into driving position within a guideway 24 at the front of the machine. Here a driving blade 25 is located to be driven against the head end of the nail within the guideway to drive the nail out of the lower end of the guideway and into the members to be secured together. One of the nails 15 is shown in full line within the guideway 24 ready to be driven, and in dot-dash outline in the fully driven-in position within the molding strip 20 and the frame 16. The driving blade 25 may be adjusted to countersink the head of the nail flush with the surface of the molding strip or as deep within the surface as desired.

In order to facilitate handling the nails 15 for loading into the magazine 22 of the driving machine, a substantial number is preferably secured together in sidewise abutment by means of lacquer or other suitable adhesive to form a "stick" of convenient length, substantially as shown in Fig. 5.

To facilitate the process of manufacturing the nails 15 and assembling them in the stick form, the heads of the nails should have means for engaging a guide bar by which the nails are maintained in alignment until they are adhered together by the adhesive, and which is substantially the counterpart of the guide bar 23 of the nailing machine. To this end, each of the nails 15 in addition to having a relatively long nail shank 27, is also formed with a small hook shaped head 28 which may have a substantially flat laterally extending crown and carries a short leg 29 extending in the same direction as the shank 27.

The ends of both the shank 27 and the leg 29 are formed with penetrating points 30 and 31, re-

spectively, by chamfering of each of their ends from respectively opposite sides to a central substantially knife edge. The edges of the points 30 and 31 preferably extend from side to side of the nail. The central or diametrical location of the point edges relative to the shank and leg extremities has been found of advantage in driving the nails straight.

The length of the head 28 and also the length 10 of the leg 29 are kept within as short limits as practicable. In a commercial form of the nail which has been found quite satisfactory for attaching screen moldings, the head of the nail has been made between about one-eighth and 15 three-sixteenths of an inch in length, outside dimension, with the leg 29 of no greater and preferably shorter length, in a nail approximately seven-eighths of an inch long. The cross-sectional dimensions of the shank and head are preferably uniform throughout the nail, and thus 20 permit full side-by-side contact of the nails 15 in the stick relationship.

A preferred material for making the nail 15 comprises a flattened steel wire. This may have 25 fairly flat longitudinal faces at the inner and outer faces of the nail, and slightly rounded side edges. The roundness of the side edges limits the engagement, and hence the adhesive connection, 30 between the edges of the nails to reasonably narrow lines so that although the nails may be handled in stick form without coming apart, they will readily detach from the stick in the driving machine under the impact of the driving blade 25.

An advantage of having the head 28 as short 35 as possible, is that only unobjectionably small countersink holes will be made in the face of the molding strip 20 and the small bit of metal of the crown of the head which may possibly be exposed will not detract from the neat, finished 40 appearance of the molding strip.

By having the leg 29 of the nail head as short 45 as possible, a definitely advantageous result is attained in the effectiveness with which the nail will hold the relatively thin and fragile molding strip 20 in place. Thus, by reference to Fig. 4, it will be seen that even though the head 28 of the nail is countersunk below the surface of the molding strip 20, the short leg 29, acting as a prong, penetrates only a short distance into the molding strip. Thereby, a substantial portion of the body of the strip 20 intervenes between the point 31 and the rear face of the strip. This is 50 of importance when it is considered that the grain of such a strip generally runs longitudinally, and for convenience in application the nails 15 are usually driven with the length of the head 28 extending lengthwise of the strip. Hence 55 there is a tendency of the section of wood 32 (Fig. 4) severed from the grain of the strip between the shank 28 and the prong 29 to shear away upon being compacted in countersinking the nail. However, since the material of the section 32 is backed up by the substantial, unpunctured grain portion of the molding strip which 60 intervenes between the point 31 of the prong and the rear face of the molding strip, the section 32 actually forms an interlocking anchorage for the hook-shaped head structure of the nail.

As a result of the interlocking relationship of 65 the section 32 of the molding strip and the hook-head 28, the nail 15 is thoroughly anchored not only by the frictional hold upon the long shank 27 driven into the frame 16, but also by the frictional hold upon the portion of the shank 27 that 70 passes through the molding strip and upon the

penetrating prong 29, and by the interlocking portion 32 of the strip. This, taken together with the fact that the nail can be made of adequate weight to withstand long weathering, assures that the nail will hold the fastened members together indefinitely.

For some purposes it may be desirable to have even less of the metal of the crown of the hook-shaped nail head liable to show at the surface of the nailed article than is the case with the relatively flat crown of the head 28. There may also, of course, be other considerations, such as the preferred or most effective shape of the nail head for engagement by the end of the driving blade of the nailing machine under certain conditions, which would dictate the particular shape of the crown of the nail. In one modified form, the head of the nail may be formed on a radius as indicated at 33 in Fig. 7. In another form, as shown in Fig. 8, the head may be substantially peaked as indicated at 34. In the modified form of Fig. 9, the head may be formed at an oblique angle as indicated at 35 more or less in the nature of a barb. In each of the forms of Figs. 7, 8 and 9, it will be evident that after the nail has been countersunk into the surface of the nailed article only a bare point of the highest portion or crown of the nail head will be near the surface of the article.

From the foregoing it will be apparent that the present invention provides a finishing nail which is of a unique construction that practically prevents the head of the nail from pulling through the nailed article. This is accomplished without compromising the effective proportions or weight of the material from which the nail is made. Thus, my novel finishing nail may be used effectively to secure articles such as insulating panels, wallboards, and the like, for which the round-headed finishing nails have been wholly impractical because of the liability of pulling through the oftentimes rather soft fibrous material of such objects. Furthermore, the nail is peculiarly well adapted to be supplied in adhered or stick form for use in a driving machine, an accomplishment which has not heretofore been possible with finishing nails.

While I have illustrated and described certain preferred embodiments of my invention, it is to be understood that I do not thereby intend to limit my invention to the specific forms disclosed, but contemplate that many modifications and alternative constructions may be made without departing from the scope and spirit of my invention.

I claim as my invention:

1. In combination with a relatively thick base member and a relatively thinner member to be nailed together, the thinner member being of relatively fragile character to the extent that when it is pierced by a pair of closely spaced nail shanks or nail-weight staple legs the partially severed material of such member lying between the nail holes is detached from or at least so weakened with respect to its attachment to the

material at opposite sides of the puncture plane that the partially severed material will afford little, if any, resistance to plug-out where said members are subjected to a relative separating force, a finishing nail having a relatively long shank extending entirely through said thinner member and anchored deeply in the base member, said nail having a head of substantially hook shape including a point penetrating only partially through said thinner member, and a substantial unpierced portion of said thinner member intervening between the end of said point and the inner face of said thinner member, said head being in engaging relation to that material of the thinner member which is partially severed by the shank and point and lies within the hook of the head, said intervening portion of the thinner member forming a solid retaining bridge across the inner end of the hole formed by said point and being integral with the adjoining material of the body including said partially severed material to reinforce said partially severed material for effecting a sound interlocking relationship with said hook-shaped head strongly resisting pulling of the head through or loose from the thinner member.

2. In combination with a pair of juxtaposed members, one of which is a relatively thin soft-textured wooden molding strip in which the grain runs longitudinally and the other of which is a substantially thicker nailing base, a finishing nail having a shank at least twice as long as the thickness of the molding strip and extending entirely through the molding strip and deep into the nailing base, an integral hook-shaped head on the outer end of said shank having the same cross-sectional proportions as the shank and extending only a short distance laterally from the shank in the same direction as the grain runs in the molding strip, the head being countersunk within the outer surface of the molding strip, the head terminating in a pointed short prong spaced from said shank to such a limited distance that, considering the diameter of the stock from which the nail is made, if said prong were projected parallel with the shank to such a distance that in the countersunk condition of the head such prong were to extend entirely through the molding strip, the material between the prong and hook would be detached and tend to be displaced as a slug in the countersinking of the head, said prong actually being substantially shorter than the thickness of the molding strip and wholly embedded therein, and a substantial unpunctured solid layer of the wood of the molding strip intervening between the point of the prong and the base-engaging face of the molding strip, such intervening solid layer being integral with and reinforcing the material of the strip that lies within the hook of the nail against plug-out in response to a pull on the strip tending to separate it from the base and draw it away from the nail.

CHARLES E. CROOKS.
